FIRE EXTINGUISHERS

Philip M. Carter, Ossining, N.Y., and Daniel Nardoza, Keyport, N.J., assignors to Leeder Manufacturing Co. Inc., Keyport, N.J., a corporation of Delaware

Application December 30, 1955, Serial No. 556,720

3 Claims. (Cl. 169—31)

This invention relates to fire extinguishers and more specifically to the discharging, filling and indicating aspects thereof.

In tank type fire extinguishing apparatus, employing either powder or liquids, where the fire extinguishing medium is held under pressure, that pressure must be maintained for extended periods of time so that it will be present to expel the extinguishing medium instantaneously when needed. Thus, the valves employed must provide a positive and continually effective seal to hold the pressure in the tank while being capable of instantaneous effective opening. Also, the valves and the actuating and mounting parts therefor must be capable of effective, intermittent operation and for closing, to positively prevent leakage of pressure after each such operation.

Besides containing the valve, various passages for discharge and recharge and for mounting other operating parts, the discharge head must protect all of them against the various possible causes of injury. It must protect them from damage resulting from striking external objects, it must protect the internal parts from the effects of weather, and from the effects of corrosive action, or other possible causes of deterioration that would in any way disturb the effective operation of the extinguisher. In addition, the discharge head and the portion of the tank to receive the same must be formed for removal and replacement of the discharge head and for effective sealing between the head and the tank when such replacement is effected.

The discharge head and the instrumentalities carried by it must be formed and related for ready assembly and disassembly should repairs and replacement of parts, or mere examination of them be necessary. It is also desirable that the discharge head include provision for indicating the pressure in the tank at all times, without having to try out the extinguisher, and it is further desirable for the operating mechanism to include simple means for setting the rate of flow for the particular size tank, and particular extinguishing medium.

Prior art extinguishers have failed to meet these needs in effective manner, though their constructions have involved highly complex and consequently expensive arrangements. Moreover, by reason of the complication of prior art discharge heads and the valve and other instrumentalities carried thereby, maintenance and repair presented substantial problems, not the least of these is the need of special tools and equipment for assembling, disassembling and adjusting the various structures.

The discharge head and related instrumentalities of the invention overcomes the drawbacks of prior art constructions and incorporates a number of advantages over such construction. All of the features of the head are simplified and made more effective than those of the prior art devices. The valve and reception of it by the head are particularly effective and are capable of being worked on in most simple and straightforward manner. The valve works effectively for intermittent operation.

2

It is self adjusting and it is effective for dry chemicals or liquid materials. The reception of the valve by the head, the provision for actuation of it, the provisions for preventing an unintentional actuation, and the protection of all of the parts against action of the elements are all incorporated in simple straightforward manner. Furthermore, the pressure condition within the tank is indicated directly by means carried by the head and the conduits for passage of the medium through the head not only provide for fully effective discharge, but also materially facilitate recharging.

It is, accordingly, the principal object of this invention to improve upon the construction and operation of discharging-filling heads for fire extinguishers.

Another object is to provide for such heads and the operating instrumentalities carried by the same which will operate in uniform fool-proof effective manner.

Another object of this invention is to provide operating mechanisms for fire extinguishers characterized by simplicity, ease of assembly and disassembly and dependability of operation over long periods of time.

Another object is to provide such mechanism which facilitates the filling of the extinguisher and provides effective indication of the condition inside of the extinguisher once it is filled.

Another object is to provide an improved valve for pressure type fire extinguishers adaptable for use with fire extinguishing mediums such as gases, liquids and powder.

Still another object is to provide an improved metering tube adaptable for use with tanks of various sizes and for discharge of the fire extinguishing medium at the desired rate.

A further object is the provision of a valve operating handle releasably secured to the valve and adapted to function as a tool in the assembly and disassembly of the valve elements.

A still further object resides in the provision of an improved safety lock for fire extinguishers to prevent accidental operation of the extinguisher.

The foregoing and other objects of the invention will in part be obvious and in part be pointed out as the description of the invention taken in conjunction with the accompanying drawing proceeds.

In that drawing:

Fig. 1 is a side elevation of a fire extinguisher in accordance with the invention showing the filler attachment applied to the discharge head.

Fig. 2 is a top plan view of the discharge head as shown in Fig. 1 but with a discharge nozzle replacing the filler attachment.

Fig. 3 is a cross section of the discharge head taken on the line 22 of Fig. 2.

Fig. 4 is a view similar to that of Fig. 3 but with the operating handle in a depressed position to illustrate the opening of the control valve.

Fig. 5 is a fragmentary cross sectional view of a portion of the discharge head taken along the line 5—5 of Fig. 2; and

Fig. 6 is an exploded perspective view of the valve operating handle and control valve assembly per se to illustrate the manner in which they cooperate in the operation of the valve and the manner in which the operating handle can be used as a wrench in disassembling the valve for maintenance and repair.

Referring now to the drawings and more specifically to Figs. 1-4 thereof, the discharge head is generally denoted by the numeral 10 and is arranged for suitable attachment to a tank 12 in which the fire extinguishing medium is retained under pressure. The term "discharge head" is used for ready reference to denote the

housing applied to the top of the extinguisher tank and includes the mechanism contained therein. Besides the discharge function, however, the housing and its contained and applied instrumentalities perform other functions such as sealing, facilitating the pressuring of the tank and indicating the pressure within the tank. Thus, the use of the term "discharge head" must be considered as being for convenience of reference and not for purposes of limitation.

The discharge head and particularly the valve of the invention operate effectively with pressures as low and as high as desired. There must be a balance of cubic inches of pressure per pound of chemical to be moved. Thus, the higher the pressure, the more chemical can be placed in a given size chamber. As examples:

A 5 pound extinguisher, using the discharge head of the invention, is filled to roughly two-thirds of its total volume and is properly pressurized to move the chemical under a pressure of approximately 150 p.s.i. to 190 p.s.i. If 6 or 7 pounds were placed in the same chamber, pressures of 250 p.s.i. to 350 p.s.i. might be required to properly pressurize the chamber and move the chemical.

Welded tanks or bottles of the type illustrated and utilizing a powder as the extinguishing medium are generally approved for such use when the pressures are as low as 170 to 190 p.s.i. When powder, such as sodium bicarbonate, is employed, the head 10 is removed and about three-fourths of the tank is usually filled with the powder. After that, the head 10 is replaced and screwed up tight whereupon the tank is charged with air, nitrogen or other suitable inert gas to a pressure of approximately 190 pounds. Since powder normally settled to the bottom of the tank, a discharge tube 13 secured to the head 10 extends down within close proximity of the tank bottom. The diameter of this tube is preselected to control the rate at which powder is discharged from the outlet 14 of the head. To accommodate for different tank sizes and different rates of discharge, tubes 13 of different internal diameters are provided. These are each equipped with a nipple 15 for threaded engagement with the bottom end of the discharge head so that a single valve may be utilized for a wide variety of shapes and sizes of tanks 12 and for any desired rate of discharge merely by providing the proper sized tube. Though a welded tank type container has been shown, it is noted as above indicated that the head and valve of the invention are effective for use with one-piece high pressure bottles. Actual tests have shown that the head and valve of the inventions are adaptable for effective use with pressures of 350 pounds or even greater.

The discharge head 10 and applied instrumentalities in accordance with the invention comprise six basic elements, namely, the valve housing 16, the valve and stem assembly 17, the operating handle 18, a fixed handle 19, a pressure gauge 20 and the "locking device" 21. The valve housing 16 has an enlarged flange portion 22 from which a tubular part 23 extends downwardly. The part 23 has external threads 24 and internal threads 25. The internal threads 25 receive an externally threaded adapter 15 carrying the discharge tube 13 which extends within the tank 12. Tubes of various diameters may be fitted to adapters such as 15 and thus be secured to the discharge head. While it is desirable to maintain a reasonably good seal between the adapter 15 and the tubular extension 23, the normal seal provided by interlocking threads has been found to be most satisfactory, though a gasket may be employed if desired.

The external threads 24 are for engagement with a corresponding threaded opening in the receiving fitting on the top of the tank or bottle 12. A tight seal is made at this position by the use of a pair of O rings 26 and 27 carried in suitable recesses 26' and 27' in the tubular part 23 below the flange 22. The O ring 26 provides side wall gasketing. Its sliding action on the surface of the mated seat of the tank fitting wipes that surface clean in order to secure a more effective seal. The O ring 27,

which when in position on the tank is wedged in the recess 27' beneath the flange 22 by a cooperating chambered surface on the tank fitting, provides an end or compression type gasketing. Either one of these gaskets pro-

vides an effective seal, while the combination of the two of them provides insurance that, though the fitting carrying them is unscrewed and replaced, a sure pressure-tight seal will be achieved. More detailed description of this structure and the gasketing will appear in a separate application of the instant applicants directed to these features per se.

The outlet passage 28 of the valve housing is provided with a tapered valve seat 29 to receive and cooperate with the valve 30 forming part of the valve assembly 17.

15 The upper end of the seat 29 terminates in a cylindrical section 31 which has an opening 32 extending out through the side thereof. This opening has an internally threaded mouth 33 for reception of a suitable nozzle 34 (Figs. 2 and 3). The nozzle 34 may be just that, or it may be a coupling for a flexible hose. In the case of powder type extinguishers wherein the powder is loaded into the tank 12 which is then closed by the application of the housing 10 thereto, the mouth 33 is used for the attachment of a gas injection adapter 35 illustrated in cross section in Fig. 1.

20 The valve assembly 17 includes, in addition to the valve head 30, a valve stem 36 extending upwardly through an opening 37 in the valve housing into an enlarged cylindrical chamber 38 in the upper end of the housing 16. This chamber has a pair of gaskets 39 and 40 seated on the bottom thereof and snugly embracing the valve stem 36. The upper end of the stem 36 has a cylindrical valve operating member 41 threadably secured to the upper end thereof. The member 41 is provided on its exterior with a rounded operating surface 41'. A spring 43 is disposed between a flange 44 on the valve operating member 41 and the gaskets 39 and 40 seated on the base of the chamber 38. The spring 43 secures the gaskets 39 and 40 in place on their seat 25 while its principal function is to urge the valve operating member 41 upwardly to put and maintain the periphery of the valve head 30 in contact with the tapered wall 29 to close the valve.

25 The flange 44 slides with respect to the side wall of the chamber 38 and the lower portion of the valve operating member 41 is guided in the chamber 38 by means of an annular cap 45 threaded onto the upper end of the housing 16. The cap is centrally perforated at 45' for the slidable reception of the shank of the member 41. The cap is sealed to the housing by means of a gasket 47 and is slidably sealed with respect to the shank of the valve operating member 41 by means of an O ring 48 disposed in a recess formed around the perforation 45'. This O ring serves as a guide for the shank of the valve operating member 41 and also as a seal against that member for preventing moisture, whether from the weather or otherwise from leaking into the chamber 38. Hence the gaskets 39 and 40, gasket 47 and the O ring 48 cooperate to prevent the escape of gas or powder into the chamber 38 or through it when the extinguisher is being operated, and prevent moisture, dust, dirt and other foreign particles from getting into the valve operating mechanism or onto the valve during storage. In this way dependable and effective valve operation is assured even though the valve is not operated for extended periods of time. The pressure within the tank 12 tends to supplement the action of the spring 48 in closing the valve and thus insures a more positive seal between the valve head 30 and the tapered cooperating wall 29.

30 The valve 30 in the illustrated embodiment of the invention is in the form of two abutting cones with a resilient washer or ring 30' disposed about the center. With this structure the resilient material 30' creates the initial seal with the tapered opening part 29 with the upward motion being limited by contact of the periphery

of the upper cone with the side walls of the taper 29. In the event the upward motion of the valve 30 in closing brings the rim of the upper conical section in contact with the tapered walls 29 then the resilient material 30' is deformed under the action of the valve and the pressure of the gas in tank 12 to insure a positive and dependable seal. The action of the pressure supplements the action of the spring 43 in keeping the valve closed tight. The details of this valve structure and the advantages achieved by it are more fully set forth in applicants' companion application directed to the valve per se and filed concurrently herewith.

The valve is opened by means of the handles 18 and 19, the latter being pivotally attached at 49 to a lug 50 formed integrally with the valve housing 16. The handle 19 has a stop portion 19' which comes into engagement with the upper surface 50' of the lug 50 to limit upward movement of the handle to the position shown in Fig. 3. The handle 18 is in the shape of an L with the free end of the short leg 51 pivoted at 52 to a lug 53 formed as an integral part of the housing 16 and on the side thereof opposite to the lug 50. The longer leg 54 of the handle 18 has an actuating surface 54' which is formed for smooth engagement with the surface 41' of the valve operating member 41 so that when the handle 18 is depressed these surfaces ride smoothly on each other. The valve assembly 17 and the valve head 30 are moved downwardly against the action of the spring 43 and against the pressure in the tank 12 to open the valve and permit the fire extinguishing medium to pass upwardly and outwardly through the discharge opening 33.

The manner in which the handle 18 and the valve operating member 41 cooperate is shown more clearly in Fig. 6. From this figure it will be observed that the upwardly extending portion 55 of the valve operating member 41 is provided with a section having flattened sides 56 whose vertical extent is somewhat greater than the thickness of the leg 54 of the handle 18. This allows for some play between the handle 18 and the member 41, for reception of the legs of the locking member 21, as will be explained hereinafter. An elongated slot 57 is formed in the leg 54 to receive the portion 55. At the end of the slot 57 away from the leg 51 it enlarges into a circular opening large enough to receive the cylindrical top of the portion 55 so that the latter can be inserted through the handle and then moved towards the short leg 51 with the section having the flattened sides 56 being slidable within the slot 57. In order to shield the upper end 55 of the valve operating member 41 against contact with extraneous objects while the extinguisher is waiting to be used, the handle member 54 is provided with a pair of lugs 59 at either side of the member 55 and which project up above it.

From the relationship between the member 55 and the handle 18 it will be seen that as the handle 18 is depressed to actuate the valve vertically, a sliding action takes place between the surface 41' of the head 55 and the surface 54' of the handle 54. By reason of this action the mechanical advantage increases as the handle lever is depressed since the fulcrum moves to the left as shown in Fig. 4 and enables the operator to hold the valve assembly in the depressed position more easily. As will appear hereinafter, the handle 18, besides being an operating member, is also used as a tool or wrench to facilitate disassembly and assembly of the valve.

Another important feature of the discharge head in the invention resides in the relationship of the pressure gauge or meter 20 to the valve housing 16. This is illustrated in Fig. 5 from which it is seen that the valve housing 16 includes a boss 60 having a threaded opening 61 therein to receive the externally threaded bushing 62 forming part of the gauge 20. The threaded recess 61 is slightly above the normal closed position of the valve head 30 but is in communication with that portion of the conical opening 29 below the valve head 30 through a small orifice or

passageway 63. In this way the internal pressure within the cylinder 12 is continuously indicated by the meter 20 whether the valve is in the open or closed position.

In order to prevent the valve from being accidentally operated by depression of the handle 54, the safety device 21 is provided in the form of a clip 64 formed of suitable spring material such as spring steel or Phosphor bronze. The clip 64 is in the shape of a U with the legs 65 and 66 having portions thereof arcuately formed as indicated at 65' and 66' to engage the cylindrical body part of the valve operating member 41. The free ends 67 and 68 of the clip are bent outwardly to facilitate the insertion of the clip about that body and between the underside of the handle 18 and the top surface of the screw cap 45. The presence of this clip beneath the handle prevents accidental depression of the handle and operation of the valve. The clip legs 65 and 66 need not hold the handle 18 up tight since the flat portions 56 on the valve operating member 41 are somewhat longer than the thickness of the handle at its slotted position. This "play" or "lost motion," between the handle 18 and the member 41 is of importance for if there were none the likelihood of unintentional opening or "cracking" of the valve would be too great. Any movement of the valve, even though quite minute, could cause loss of pressure. Hence, the clip need only be wide enough to raise the handle surface 54' out of contact with the surface 41' of the valve operating member.

Insertion and withdrawal of the clip 64 is accomplished by grasping an enlarged outwardly extending ring 70 secured to the clip. The clip and ring are preferably protected against loss by being connected to the body of the valve by a chain or other suitable means.

To disassemble the valve and its operating elements 35 the cotter pin 52' (Fig. 2) is removed from the pivot pin 52 and that pin is then withdrawn from the cooperating openings in the handle 18 and lug 53 of the body 16. The handle 18 is then slid along until the opening 58 registers with the portion 55, whereupon the handle can 40 be lifted up and removed. The cap 54 is then unscrewed from the valve body 16. After the cap 45 has been removed, the handle is then reversed and reengaged with the valve operating member 41 with its slot 57 engaging the flats 56. The short leg 51 of the handle 18 ends 45 upwardly, for use in unscrewing the member 41 from the valve stem 36. When this has been done the spring 43 can be lifted out while the valve head 30 and operating stem 36 are dropped down and out of the valve housing 16. The reassembly of the valve in its housing is, of 50 course, accomplished in the reverse manner with the only tool necessary to effect both assembly and disassembly being the handle 18. Pliers or a wrench may, of course, be required to remove or apply the cap 45.

From the above it is apparent that this new and improved discharge head and applied instrumentalities provide a highly effective and dependable mechanism for fire extinguishers. They not only provide a secure and permanent seal against the loss of pressure within the tank 12 but enable quick and easy total, or partial, discharge 55 operation, without resultant leakage of pressure, upon withdrawal of the clip 64 and depression of the operating lever 18. Because of the simplicity of the mechanism and structure and the utilization of a sealed chamber to house the basic valve operating members, the presence of 60 dust and dirt in the surrounding atmosphere or even corrosive gages for extended periods of time will not affect the ease of operation of the valve. In the event of oxidation of the exposed portion of the valve operating member 41, the leverage provided by the handle 18 to operate the valve is more than sufficient to overcome any interference. In addition, the pressure within the tank aids in maintaining the valve in closed position and assists the spring 43 in doing so.

Though in the foregoing description and accompanying 75 drawing, specific structure embodying the invention have

been shown and described, it is of course to be understood that such showings are for illustrative and not limiting purpose and that alternatives and variations thereof as suggest themselves to those skilled in the art could be employed without departing from the spirit and scope of the invention.

Speaking more generally, since certain changes in carrying out the above method and in the constructions set forth, which embody the invention, may be made without departing from its scope, it is intended that all matter contained in the above description or shown in the accompanying drawing shall be interpreted as illustrative and not in a limiting sense.

Having described our invention, what we claim as new and desire to secure by Letters Patent is:

1. In fire extinguisher construction, in combination, a discharge head directly connectable with the top of the container of a fire extinguisher including an upwardly and inwardly inclined valve seat, a valve member having a portion formed for engaging said seat in a metal to metal line contact on the upward movement of said valve member with respect to said seat, said valve member carrying a resilient packing element below said engaging portion for contacting said seat below said line to line contact, a stem extending upwardly from said valve member, an operating handle pivoted to said discharge head and formed for the operation of said valve by a downward movement thereof, and interengaging means between said valve stem and said handle for translating the movement of said handle to said valve, said interengaging means including means for precluding upward movement

5

10

20

25

30

of said handle without consequent upward movement of said valve stem whereby when one lifts the fire extinguisher, including said container, by said handle any load imposed upon said valve member will be absorbed through said metal to metal line contact thereby protecting said packing element of said valve against injury.

2. Fire extinguisher construction as in claim 1 and said valve seat and said valve member having conical surfaces inclined in the same direction, the incline of the cone of said valve member being greater than that of said valve seat, said valve member being formed of metal and said resilient packing element being carried by said valve member below the base of said cone and extending out a short distance beyond said base.

3. Fire extinguisher construction as in claim 1, said interengaging means between said valve stem and handle including said handle being recessed for the reception of said valve stem, said valve stem having a portion received in said recess and said portion being formed with a laterally extending shoulder for engagement with said handle at the side of said recess.
